UNITED STATES PATENT OFFICE

FRANK FEWINS, OF LOS ANGELES, CALIFORNIA, ASSIGNOR OF ONE-FOURTH TO DANIEL J. W. HUNTINGTON, OF LOS ANGELES, CALIFORNIA

HAIR CUTTER

Application filed November 21, 1928. Serial No. 320,951.

This invention relates to barbers' equipment, and pertains more particularly to hair cutters of the shear type.

My invention contemplates an improved hair cutter of the class described in my United States Letters Patent No. 1,615,328, issued to me January 25, 1927.

Among the objects of this invention, it is intended to provide a superior device over the one set forth in my above cited patent.

Another object is to provide a power device for trimming hair that may be used in lieu of the ordinary barber shears with greater facility and speed than is now possible.

Another object is to provide a device having power driven shears adapted to perform a combined drawing and shearing action and to cooperate with a comb mounted upon said device in such a manner that the comb may be controlled by the same hand that holds the device for operation.

Another object is to provide a device of the character described that is simple, durable, has few moving parts, presents a neat workmanlike appearance, is small and compact and may be easily held by one hand and such a device that lends itself readily to economy of manufacture.

Briefly stated, my invention may be said to reside in the parts, arrangement of parts and in the combination of parts, to produce a hair trimmer of the character described, having the foregoing recited characteristics.

The foregoing recited objects and advantages, together with any subsequent features that may be developed in the specifications and claims, constitute my invention, one embodiment of which is shown and illustrated by way of example in the accompanying drawings, in which:

Fig. 1 is a perspective view of my device, complete;

Fig. 2 is an end elevation of the same;

Fig. 3 is a fragmentary side elevation showing the comb mechanism particularly;

Fig. 4 is a fragmentary end view, showing the shear actuating arrangement.

Referring to the drawings and particularly to Fig. 1, my device is seen to comprise

three major elements, namely, the handle or gripping member A, the shears B and the comb C.

The coordinating elements whereby these major elements are combined into a functioning unit, will now be fully described.

The handle A is shown as being ovoid in shape, but the shape is optional; there being no requirement in this respect beyond the ease of gripping. Passing through the handle lengthwise, is a rotatable shaft 10 which, at its outer end, may be adapted to make a coupling with any ordinary flexible drive connection (not shown). Mounted at the opposite end of the handle A is a plate 11 suitably secured thereto and having a tongue 12 extending across the face near the upper edge thereof. In mounting the stationary shear 13, the tongue 12 fits into a groove 14 on the base 20 of the shear 13 and serves as a rigid guide mounting for the shear which is rigidly held in place by a screw threaded bolt 15 passing through said tongue and groove. The bolt 15 is further utilized to hold the clip 16 against the base 20 of the stationary shear 13 in such a manner that the clip 16 may be rigid. The clip 16 is provided with a barrel 21 adapted to rotatably receive the extended portion 22 of the top of the comb C. The end of the portion 22 is bent up at right angles as shown at 23 and is provided with a ring 24 at its outer end. It is evident that the ring 24 lies in a position whereby a finger of the hand holding the device may be inserted therethrough and the angle of the comb controlled, thereby determining the length of the hair left uncut. This feature is best illustrated in Fig. 3, wherein the dotted positions show the two extreme positions of the comb.

The actuating mechanism for the movable shear 28 comprises an eccentric pin 28 mounted on the end shaft 10. The shear 28 is then slidably and pivotally mounted on a bolt 30 by means of a slot 31 in the base of the shear 28. To allow for the free sliding and rotation of the shear 28, the base 20 of the fixed shear 13 is cut away as shown at 32. As best shown in Fig. 1, the bolt 30 which is the pivot point for the shear 28 is carried in the base 20 of

the shear 13. This structure permits of fine adjustment of the stroke of the shear 28. It is obvious that if the entire assembly of the shears B is slid on the tongue and groove 12 and 14, respectively, the stroke of shear 28 is accordingly modified and becomes either longer or shorter, according to whether the pivot is removed from or brought nearer the eccentric.

10 Another feature of this shear arrangement resides in the cutting action which is a sliding as well as a shearing action. The combination of an eccentric and a slideable pivot point, causes the shear 28 to draw along the 15 shear 13 at the time of shearing, thus imparting a double cutting action to the shear; namely, a drawing and a shearing action. This feature is best illustrated in Fig. 4 wherein the dotted line position shows the 20 location of the shear 28 in its altered position.

It will be seen that the invention embodies a simple hair-cutting instrument in which both the stationary blade and the movable 25 blade have shank portions which are of less length than their cutting portions, the power driven shaft being eccentrically connected with the shank of the movable shear, said shaft extending at substantially a right angle 30 to the plane in which the movable shear moves.

The foregoing description is confined to one embodiment of my invention, but inasmuch as various alterations and changes can 35 be made therein, I reserve the right to make such modifications, and refinements as do not depart from the scope of the specifications nor the spirit of the claims.

I claim:

40 1. In a hair cutting mechanism, a handle, a stationary shear fixed to said handle at right angles thereto, a movable shear co-operating with said fixed shear to perform a cutting action, and power operated mechanism for driving said movable shear, said mechanism comprising a shaft adapted to be driven by power, an eccentric pin on the end of said shaft engaging the base of said movable shear and a pivot point adapted to slidably and pivotally engage said movable shear at a point intermediate said eccentric point and the cutting edge of said movable shear.

45 2. In a hair cutting mechanism, a handle, a stationary shear fixed to said handle at right angles thereto, a movable shear co-operating with said fixed shear to perform a cutting action, a comb having finger control means controllably mounted on said fixed shear, and power operated mechanism for driving said movable shear, said mechanism comprising a shaft adapted to be driven by power, an eccentric pin on the end of said shaft engaging the base of said movable shear and a pivot point adapted to slidably and pivotally engage said movable shear at a

point intermediate said eccentric point and the cutting edge of said movable shear.

3. In a hair cutting mechanism, a handle, a stationary shear fixed to said handle, a movable shear cooperating with said fixed shear to perform a cutting action, a comb having finger control means controllably mounted on said fixed shear, and power operated mechanism for driving said movable shear, said mechanism comprising a shaft adapted to be driven by power, an eccentric pin on the end of said shaft engaging the base of said movable shear, and a pivot engaging said movable shear at a point intermediate said eccentric pin and the cutting edge of said movable shear.

In testimony whereof, I have affixed my signature.

FRANK FEWINS.
